UNITED STATES PATENT OFFICE.

CHARLES A. GOOZEY, OF PROVIDENCE, RHODE ISLAND, ASSIGNOR TO B. A. BALLOU & COMPANY INC., OF PROVIDENCE, RHODE ISLAND, A CORPORATION OF RHODE ISLAND.

CHAIN-CONNECTOR.

1,246,911.

Specification of Letters Patent.

Patented Nov. 20, 1917.

Application filed June 9, 1917. Serial No. 173,748.

To all whom it may concern:

Be it known that I, CHARLES A. GOOZEY, a citizen of the United States, and resident of the city of Providence, in the county of Providence and State of Rhode Island, have invented certain new and useful Improvements in Chain-Connectors, of which the following is a specification.

This invention relates to connectors for joining together the ends of chains such as neck chains or other chains for personal wear, and the object of this invention is to provide such a connector comprising two members one slideable within the other, one of said members having a slot in its edge for the reception of one of the end links of the chain, and the other member having a portion adapted to close or open the mouth of said slot by a relative sliding movement of the parts. By this construction the greater tension on the chain the more securely is the connector locked.

With these and other objects in view, the invention consists of certain novel features of construction, as will be more fully described, and particularly pointed out in the appended claims.

In the accompanying drawings:

Figure 1 is a side elevation of the connector showing the body member in section and the keeper in open position.

Fig. 2 is a side elevation of the keeper member detached, showing one of its arms out of alignment with the other.

Fig. 3 is a perspective view of the body member with the keeper removed.

Fig. 4 is a modification showing a sectional side elevation of the connector of sheet stock.

Referring to the drawings, 10 designates the body member of my improved connector which is constructed preferably of a short length of tubing having its walls pressed nearly together, as illustrated in Fig. 3, 45 forming two longitudinal channels 11 and 12 in opposite edges thereof. One of the side edges near one end of this body is provided with a slot 13 into which the end link of the chain is adapted to be passed. This 50 slot is undercut slightly as at 14, to receive the bend of the end link 23 of the chain, illustrated in dotted lines in Fig. 1, when pressure is being brought thereagainst to open the connector.

The keeper member 15 may be constructed

in any suitable way but is preferably made of spring wire bent in a loop form, one end of the loop being bent into the shape of an eye 16 to which the end link 24 of the chain is attached. The sides of this keeper consist 60 of two arms 17 and 18, the arm 18 being adapted to set in the channel 12 of the body and is of a length to extend through the body member, and its end 19 is provided with a return bend, its extremity 20 being 65 positioned and of a length to enter the mouth of the opposite longitudinal channel 11.

The opposite arm 17 of this keeper is naturally offset out of alignment with the arm 18 thereof so that when the keeper is 70 positioned in the body, this short arm 17 exerts a spring tension in these channels thereby providing friction sufficient to retain the keeper in any adjusted position. The short arm 17 is of a length to leave a 75 space 21 between it and the end 20 of the opposite arm of a width substantially equal to the mouth of the slot 13.

In positioning this keeper in the body member, the side walls 25 of the latter are 80 left sufficiently open so that the keeper may be passed therethrough after which these side walls are closed substantially together thereby limiting the closing movement of the keeper to a stroke sufficient to permit its 85 end 20 to close the mouth of the slot, the opening movement of the keeper being limited by the shoulders 22 bringing up against the end of the body.

The connector of my improved construction has a number of advantages over other chain connectors, in that by forming the body member of a piece of tubing the necessity of soldering is entirely obviated, and as the keeper is bent up from spring wire it 90 retains its original hardness and therefore its spring tension is permanent to serve as a constant friction in retaining the keeper in adjusted position.

By attaching one end of the chain to the 100 end of the keeper opposite its closing end and the opposite end of the chain in the body of the connector, it will be seen that the greater the tension on the chain the more securely is the keeper held in closed position. Then again by my improved construction the keeper member may be slid to open position by pressure being brought to bear on the two end links 23 and 24 of the chain, thereby sliding the keeper in its body 105 110

to open the mouth of the slot, permitting the link 23 to be disengaged therefrom, but as the chain itself, to which the connector is attached is always flexible there is no possibility of the connector being accidentally moved to open position after having been closed by any manipulation of the chain itself.

I have described the keeper member of the connector as formed of wire and adapted to slide in longitudinal channels in the body portion, but the keeper member 26, illustrated in Fig. 4, may be formed of sheet stock and mounted to slide in a corresponding slot in a body member 27 also formed of sheet stock if desired.

The foregoing description is directed solely toward the constructions illustrated, but I desire it to be understood that I reserve the privilege of resorting to all the mechanical changes to which the device is susceptible, the invention being defined and limited only by the terms of the appended claims.

25 I claim:

1. A chain connector comprising a channeled body member having a link-receiving slot in its edge, a keeper slidably mounted in said channel having an eye at one end and an edge link-receiving opening adjacent its opposite end, said edge opening being adapted to register with the slot in said body, and said keeper being provided with a longitudinally disposed arm adjacent its edge

opening adapted to enter the channel in said body member and close its edge opening when said member is moved to its outward position.

2. A neck chain connector comprising a single piece of wire bent to form an elongated loop having two parallel arms one of which has a link-receiving opening through it, a sleeve like body member slidably mounted upon and surrounding said arms and having a link-receiving slot in its edge adapted to register with the corresponding opening in said loop whereby the slot and opening in both member and loop may be controlled by a relative movement of these parts. 50

3. A neck chain connector comprising a single piece wire bent to form an elongated loop having two parallel sides one of which has a link-receiving opening through it, a sleeve like body member slidably mounted on both of said arms and having a slot in its edge adapted to register with the opening in said loop whereby the opening in both member and keeper may be opened or closed by a relative movement of these parts, the opposite side walls of said sleeve member being set inward to form a stop to limit its endwise sliding movement. 55

In testimony whereof I affix my signature in presence of a witness.

CHARLES A. GOOZEY.

Witness:

HOWARD E. BARLOW.
